UNITED STATES PATENT OFFICE.

GEORGE WASHINGTON HADLEY, OF CHICOOPEE FALLS, MASSACHUSETTS.

GUN-SIGHT.

SPECIFICATION forming part of Letters Patent No. 362,956, dated May 17, 1887.

Application filed February 24, 1887. Serial No. 224,712. (No model.)

To all whom it may concern:

Be it known that I, GEORGE WASHINGTON HADLEY, of Chicopee Falls, in the county of Hampden and State of Massachusetts, have invented certain new and useful Improvements in Gun-Sights, of which the following is a specification.

My present invention relates to sights for rifles; and the invention consists in certain novel features, hereinafter more fully described and claimed.

Figure 1 is a front elevation of the sight complete. Fig. 2 is a vertical section of the same on the line $x-x$ of Fig. 1. Fig. 3 is a face view 15 of the eye-piece detached. Fig. 4 is a rear face view of the rotating disk, shown detached; and Fig. 5 is a transverse vertical section of the eye-piece and rotary disk enlarged, to more 20 clearly show the details of construction; Fig. 6, a similar view, showing a slight modification.

This invention relates to that class of sights for rifles which are usually denominated "peep sights," and may be considered as an 25 improvement on the sight for which Patent No. 172,465 was issued to me on the 18th day of January, 1876.

The object of my present improvement is to provide a series of different-sized peep-holes, 30 so arranged that either of them can be used at will, and to so construct and arrange the disk in which these holes are formed that it can be applied to and used in connection with the eye-piece of my former sight, or one constructed 35 on the same general plan, and so that the disk can be adjusted whenever desired without removing any of the parts.

It is well known to hunters and others using rifles that a larger peep-hole is desirable on a 40 cloudy or foggy day than on a bright or sunny day, and vice versa. It is therefore an object to have a sight that can be readily adjusted for different distances, and which can also be quickly 45 adjusted so as to use the different-sized peep-holes. To accomplish these results, I make my improved sight as follows:

I make the leaf or standard A with a slide, J, with rack and pinion for adjusting the eye-piece I vertically, as shown in Figs. 1 and 2, and 50 as fully described in my former patent. In the former case the eye-piece I was provided with a single central peep-hole, e, which could not be

varied in size. I now form this eye-piece with a circular recess, t, in its front side, as shown in Fig. 3 and in section in Figs. 2 and 5, this recess including within its boundaries the fixed peep-hole e, as shown. I then provide a disk, h, of a size to just fill this recess, as shown in Figs. 1 and 3, and form in it a series of different-sized holes, 1, 2, 3, 4, 5, and 6, more or less 60 in number, as shown in Figs. 1 and 4, these holes being made in a circle coinciding with the stationary central hole, e, of the eye-piece I, so that by turning the disk h in its recess any one of the holes in the disk h may be brought 65 opposite the central hole, e, of the eye-piece.

In order to enable the disk to be readily and easily adjusted, and be held securely in position when adjusted, I secure the disk in place by a screw, b, under the head of which, and in 70 a small central recess in the face of the disk h, I place a small spiral spring, l, as shown more clearly in Fig. 5. In the bottom of the recess t, I secure a small round-pointed pin, n, as 75 shown in Figs. 3 and 5, and in the back of the disk h, I make a series of cavities, o, arranged in a circle, as shown in Fig. 4, of such a size as to permit the pin or projection n to engage therein when the disk is turned to the proper position, as represented in Fig. 5. It will of 80 course be understood that the relative position of these cavities o and the pin n are arranged in relation to the peep-holes in the disk, so that when the pin n is seated in one of the cavities o one of the peep-holes in the disk h will be 85 directly opposite the central hole, e, of the eye-piece. To enable the disk to be readily turned, it has a groove, i, cut across its face, as shown in Fig. 1, and for convenience I provide a small flat key, k, (shown detached,) the end of which 90 can be inserted in the groove and thus turn the disk, though it is obvious that it can be turned by a knife-blade or any similar implement. Instead of the slot and key, a small pin may be made to project from the face of the disk, by 95 which to turn it, if preferred; or by making the cavities o in the disk I the pin n may be put through the disk h, with its ends projecting from opposite sides of the same, in which case the inner end will serve as a stop by engaging in the cavities o, while its opposite projecting end may be used as a means for moving the disk, as shown in Fig. 6.

It will readily be seen that the spring l will 100

permit the disk to rise slightly from its seat when turned, as it must to disengage the pin *n* from the cavity *o*, in which it rests, and that as soon as the disk is turned far enough to bring the next hole in line the spring will cause the pin *n* to enter the cavity which has been brought opposite, and thus lock and hold the disk in place until again moved.

By this construction I produce a sight that can be adjusted vertically, and in which a different-sized peep-hole can be brought into use whenever desired without detaching or changing any of the parts.

I am aware that disk-sights having a series of holes arranged to give different elevations have been described, and also that a disk having different-sized holes has been described, and therefore I do not claim either of these, broadly; but,

Having thus fully described my invention, what I do claim as my invention is—

1. The combination, in a gun-sight, of the

concave eye-piece *I*, provided with a central hole, *e*, and a recess, *t*, for the disk *h*, and the disk *h*, provided with a series of different-sized holes, said disk being pivoted in the recess with its front face flush with the face of the eye-piece, substantially as shown and described.

2. The combination, in a gun-sight, of the eye-piece *I*, the rotary disk *h*, provided with a series of different-sized holes, said disk being pivoted to the eye-piece by a screw, *b*, having a spring, *l*, mounted thereon, to press the disk against the eye-piece, and one of said parts being provided with a series of cavities, *o*, and the other with a pin, *n*, arranged to engage in said cavities for the purpose of permitting the disk to be readily adjusted forward or back and holding it securely in position when adjusted, substantially as shown and described.

GEORGE WASHINGTON HADLEY.
